UNITED STATES PATENT OFFICE.

JAMES R. OLINGER, OF DEL REY, CALIFORNIA.

ADJUSTABLE SUPPORT FOR MIRRORS.

1,253,517.

Specification of Letters Patent. Patented Jan. 15, 1918.

Application filed June 28, 1917. Serial No. 177,528.

To all whom it may concern:

Be it known that I, JAMES R. OLINGER, a citizen of the United States, residing at Del Rey, in the county of Fresno and State of California, have invented certain new and useful Improvements in Adjustable Supports for Mirrors, of which the following is a specification.

This invention relates to adjustable mirror supports.

The object of the invention is to provide a simply constructed and efficient device of this character which will permit of convenient adjustment whereby the mirror may be readily positioned as conditions may require.

Another object is to construct a support of this character capable of supporting other objects in connection with the mirror.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a side elevation of a support constructed in accordance with this invention showing the mirror in perpendicular position,

Fig. 2 is a front elevation thereof, and

Fig. 3 is a top plan view with parts broken out.

Fig. 4 is a detail side elevation of a slightly different form of the invention.

The support constituting this invention comprises a rod 1 suspended vertically on a supporting base plate 2 which is here shown T-shaped in construction, although obviously it may be rectangular or of any other desired configuration. This plate 2 has attaching eyes 3 at the upper edge of the head 4 thereof through which fastening elements may be passed for securing the plate to the wall or to any other suitable support.

Hinged shelves 5 are carried by the lower edge of this head 4 and are adapted to fold upwardly into closed position when not desired for use and are so hinged that they will open downwardly and when in open position will abut at their rear edges against

the front face of head 4 as is shown clearly in the drawings.

A rod attaching bracket 6 is carried by the head 4 of plate 2 and is here shown inverted U-shaped, one leg being secured to the front face of head 4, preferably in alignment with the shank 4' of plate 2 and the other leg of said bracket carries a detachable clip 7 on its front face, here shown secured by bolts having wing nuts 8 to provide for the separation of the clip 7 to permit the insertion and removal of the upper end of rod 1.

The rod 1 which may be of any desired length according to the length of the attaching plate has its lower end bent at right angles to form an arm 9 which is designed to pass through the lower end of shank 4' of plate 2 and is here shown secured by nuts as 10, one of which is arranged on the front face of shank 4' and the other on the rear face thereof as is shown clearly in Fig. 1.

This rod 1 is preferably provided with annular grooves 11 throughout the length thereof, although not necessarily so, which are designed for a purpose presently to be described and are shown in Fig. 4.

A hanger 12 is mounted on the rod 1 and is designed to slide and rotate thereon. This hanger 12 comprises a sleeve 13 having an obliquely disposed upwardly extending arm 14 and a downwardly extending curved tubular handle 15.

The free end of arm 14 is preferably flattened and apertured and is designed to extend between the furcations 16 of a T-shaped mirror engaging member 17, the head of which is detachably connected with the back of the mirror 20, being preferably secured thereto by wing nuts 18 to provide for its ready removal and the replacement thereon of another when found desirable. By so mounting this mirror, mirrors of different sizes may be supported on rod 1 or any other suitable object may be carried thereby.

Yieldable means for connecting the hanger 12 in adjusted position on the rod 1 is shown in the form of a plate spring 19, which is here shown secured to sleeve 13 by a clamping collar 21, although it may be obviously secured thereto in any other suitable or desired manner. The free end of this spring 19 has a tooth 22 formed by bending the end of the spring and which is designed to spring into one of the annular grooves or corruga-

tions 11 in rod 1 to reliably connect the hanger 12 to the rod in any desired position thereon, or it may frictionally engage the ungrooved rod.

6 It is to be understood that this spring 19 is made of sufficiently heavy material to reliably retain the hanger 12 and the mirror carried thereby in adjusted position, but if found necessary, a plurality of such springs 10 may be provided.

The handle 15 is preferably constructed in tubular form so that a pin cushion or any other suitable article may be supported thereby by inserting a connector within said handle. No such object is shown herein, however, as it constitutes no part of the invention.

In the operation of this improved support, the rod 1 having been mounted on plate 2 as shown in Figs. 1 and 2, the hanger 12 is slipped on to the rod before the clip 7 is connected with the bracket 6. This hanger may then be adjusted both longitudinally and laterally by moving it up or down on the rod 1 and it will be held in adjusted position by the engagement of the tooth 22 with one of the grooves 11. To operate the hanger, all that is necessary is to grasp the downturned handle 15 and force the hanger 30 up or down at the will of the operator.

When this hanger has been positioned as desired, the mirror may be tilted at an angle either up or down by grasping it and turning it in the desired position where it will 35 be held by friction, or if desired, the thumb nut which connects it may be tightened to lock it in adjusted position on the arm 14.

From the foregoing description, taken in connection with the accompanying drawings, 40 the advantages of the construction and of the method of operation will be readily apparent to those skilled in the art to which the invention appertains and while I have described the principle of operation of the 45 invention together with the device which I

now consider to be the best embodiment thereof, I desire to have it understood that the device shown is merely illustrative and that such changes may be made as are within the scope of the claimed invention. 50

I claim:

1. A support of the class described comprising a base plate, an inverted U-shaped bracket connected at one leg to said plate with its other leg extending laterally therefrom, a clip detachably carried by said last mentioned leg, a rod having one end engaged with said plate and its other end disposed between said clip and leg, and an article supporting hanger adjustably mounted on 55 said rod.

2. A support of the class described comprising a T-shaped base plate, means for attaching said plate to a support, foldable shelves carried by the head of said plate and spaced longitudinally from each other, a rod mounted on said plate and extending between said shelves and spaced laterally from the front face of the plate, and an article supporting hanger adjustably mounted on 60 said rod.

3. A support of the class described comprising a suitably suspended rod, a hanger mounted thereon and constructed in the form of a sleeve having a curved downturned 75 hand grip at one end and an upwardly extending obliquely disposed arm at the other end, a T-shaped article supporting member having its shank bifurcated and straddling the free end of said arm and pivotally connected therewith, and rod engaging means carried by said sleeve for holding it in adjusted position on the rod.

In testimony whereof I affix my signature in presence of two witnesses.

JAMES R. OLINGER.
